UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-LIFT CONTAINER.

Application filed April 24, 1919. Serial No. 292,303.

To all whom it may concern:

Be it known that I, THOMAS LUND, a citizen of the United States, residing at Beverly, in the county of Essex and State of Massachusetts, have invented certain Improvements in Heel-Lift Containers, of which the following description, in connection with the accompanying drawings, is a specification, like reference characters on the drawings indicating like parts in the several figures.

This invention relates to containers and particularly to crates for facilitating the expeditious handling of heel lifts in connection with modern machinery.

Formerly lifts were cut by relatively slow methods and placed in barrels or bins and were handled individually as fed by hand to machines for subsequently treating them, or were handled by the girls who assembled them into heels. Lifts are now cut from sheets of leather-board by rapidly running machines which deliver the product in ordinary arrangement in horizontal columns from which they are transferred, still in column arrangement, to crates in which they are laid, several columns wide and several tiers high, the crate being of a size to hold what a man can conveniently lift. The crates are moved as required to the machines for subsequently operating upon or using them, such as lift gouging machines and heel builders, which machines are provided with magazines from which the lifts are fed automatically. By thus keeping the lifts continuously in ordinary arrangement individual handling of lifts is eliminated and much time saved over old methods. As the attendants transfer the columns of lifts to the crates and remove them to the machine magazines considerable time is lost and some injury to the fingers of the attendants is caused in handling the columns because an entire column can not be fitted into the crate or removed therefrom at one operation. Instead, a part length column has to be introduced and then enough more wedged in to fill out the column, some of the first ones tipping over while the remainder are being reached for; and in transferring the lifts to the machine magazine a handful must be taken out of the middle of the column before the attendant can get his fingers down at the two ends to grasp and raise the remainder of the column.

The object of this invention is to so improve heel lift crates that lifts in columns can be readily introduced and removed as units. To this end, the illustrated embodiment of the invention comprises a crate having opposed interior walls provided with finger channels alternating with vertical lift engaging ribs. For the full advantage of the invention, the channels and ribs are preferably so related as to present at least two finger channels in each of said walls for each column of lifts, and preferably the finger channels in the two opposed walls will be approximately opposite to each other and in line with the center of the column. In other words, the channels are so positioned relatively to the diameters of the lifts as to enable the columns to be grasped at the middle of their ends.

Illustrative examples of the invention are shown in the drawing in which Fig. 1 is a plan view of a crate constructed according to my invention, said crate having three columns of lifts packed therein.

Fig. 2 is a broken out perspective view illustrating the method of either inserting or removing a column of lifts;

Fig. 3 is a detail perspective illustrating a modification hereinafter described.

Referring first to Figs. 1 and 2 the end members 5 of the crate are each provided with vertical channels 6 each of which channels is wide enough to admit a man's finger. The channels 6 are separated by ribs 7 against which the endmost lifts of the column of lifts 8 rest. The ribs may be narrowed so that the finger channels may be close enough together so that even for small lifts at least one finger channel will be provided opposite each end of the column.

In Fig. 3 the construction is substantially the same excepting that instead of grooving wall members of the crate to form the channels and ribs, a corrugated plate may be employed consisting of a lining sheet formed to provide channels 6 and ribs 7, the ends of the sheet being so attached to other wall members of the crate as to strengthen the crate. In Fig. 3 the end of the lining is shown as having a flange 9 secured to a side wall 10 of the crate by suitable fastenings 11. This structure enables crates already made to be readily adapted for the use described by simply lining two opposite walls with the corrugated plates.

With either construction the workman has the great advantage that he can pick up from the stacking trough of the lift cutting machine a full length column of lifts (which may be indicated by gage marks on the trough and which may be a unit quantity of lifts) and while holding them in horizontal column formation, lift the column bodily into the crate because his fingers 10 can fit into the finger channels at either end of the crate. Similarly in transferring lifts from the crate to a magazine of a gouging machine or a heel building machine the attendant can stick a finger or fingers 15 into the finger channels 6 at each end of the column, and lift the entire column bodily out and place it in the machine magazine in less than half the time required with the common crates to pick out a handful of lifts to loosen the column and then after straightening up the remainder seize them by the ends of the shortened column 20 as he does now with the ordinary crate.

It is to be understood that I do not limit

myself to the particular proportions indicated in the drawings as the same may be variously modified according to the size of the lifts or according to the preferences of users.

Having explained the nature of this invention and described constructions embodying the same in economically advantageous forms what I claim is:

A container for horizontally-arranged stacks of leather blanks of different sizes, 35 said container having a flat bottom and a plurality of vertical finger channels arranged in the inner faces of the walls opposite the ends of the stacks in such a manner that at least one channel in each of said 40 walls will come opposite the end blanks of a stack regardless of the size of the blanks, to facilitate removal of the blanks as described.

In testimony whereof I have signed my 45 name to this specification.

THOMAS LUND.
